UNITED STATES PATENT OFFICE

MICHAEL F. GLEESON, OF WORCESTER, MASSACHUSETTS.

HINGED LAST.

SPECIFICATION forming part of Letters Patent No. 747,162, dated December 15, 1903.

Application filed June 10, 1901. Serial No. 63,876. (No model.)

To all whom it may concern:

Be it known that I, MICHAEL F. GLEESON, a citizen of the United States, residing at Worcester, in the county of Worcester and 5 State of Massachusetts, have invented a new and useful Hinged Last, of which the following is a specification.

This invention relates to that form of lasts having the fore and heel parts thereof connected together by a hinge-joint; and the especial object of this invention is to provide a strong, simple, and efficient form of hinge for connecting the fore and heel parts of a last together, which can be readily and conveniently inserted into place, and in which the parts are held in place by being fitted into sockets in the fore and heel parts of the last, respectively.

A further object of this invention is to construct a hinge-joint so as to accommodate a coiled spring for normally holding the parts of the last in line with each other.

To these ends this invention consists of the hinged last and of the combinations of parts 25 therein, as hereinafter described, and more particularly pointed out in the claims at the end of this specification.

In the accompanying drawings, Figure 1 is a side view, partially broken away, of a 30 hinged last constructed according to this invention. Figs. 2 and 3 are detail perspective views of the butt-pieces forming part of the three-piece hinge preferably employed. Fig. 4 is a perspective view of the hinge center piece or disk. Fig. 5 is a perspective view 35 of a modified construction of hinge center piece made in the form of a tube for receiving a coiled spring. Fig. 6 is a perspective view of the form of spring which can be employed in connection with the center piece illustrated in Fig. 5 for normally holding the fore and heel parts of the last in line with each other, and Fig. 7 is a view of a complete hinge constructed according to my invention with a spiral spring therein for holding the fore and heel parts of the last in line with each other.

In the use of hinged lasts considerable difficulty has been experienced in securing a 50 form of hinge or joint which is strong enough for the purpose and which can be secured in

place with sufficient exactness and rigidity to produce the desired results.

In most of the hinged lasts which are now employed the hinge blades or wings are inserted into horizontal cuts or recesses from 55 one side of the last.

The especial object of my present invention is to provide a cheaper and more reliable form of hinge-joint, and to accomplish this 60 object the hinge-joint which I preferably employ comprises two butt-pieces and a cylindrical hinge center piece, these parts being constructed so that when inserted into vertical recesses in the fore and heel parts of the 65 last the hinge center piece will extend into both the fore and heel parts of the last, so that the parts of the hinge-joint will be prevented from separating and so that the parts may be permanently secured together by fastening the butt-pieces in place by means of 70 transverse pins.

The hinge center piece ordinarily has the form of a solid disk, although in some cases I prefer to use a tubular hinge center piece 75 which will provide a socket for receiving a coiled spring to hold the parts of the last in line with each other.

Referring to the accompanying drawings and in detail, a hinged last constructed according to my invention, as herein illustrated, comprises a fore part 10 and a heel part 11. The fore and heel parts of the last are separated by a wedge-shaped recess, permitting the fore and heel parts to be connected or 80 joined together by a hinge. The form of hinge which I preferably employ and as herein illustrated comprises two flat metallic butt-pieces 12, which are perforated to receive transverse pins and provided with a ring or 85 annulus for inclosing a hinge center piece of considerable area. The hinge center piece preferably consists of a cylindrical piece or disk 14, and the parts of the last are so proportioned that when fitted into vertical sockets 90 in the fore and heel parts of the last, respectively, and the butt-pieces pinned in place by the transverse pins 15 the parts will be permanently secured together to form a 95 strong and efficient hinge-joint. One especial advantage in the use of a three-part hinge of this construction resides in the fact that the 100

pieces may be stamped or punched out of sheet metal with comparatively little expense and may be secured in place with as much if not greater ease than the forms of 5 hinges that have heretofore been employed.

When it is desired to employ a spring for holding the parts of the last in line with each other, the hinge center piece provides a convenient location within which a coiled spring 10 may be housed, and when such a construction is desired the hinge center piece may be made in the form of a tube 16, having notches 17 for receiving and permitting the play of the arms of a coiled spring 18, the ends of 15 which may be seated in sockets or holes 19 in the butt-pieces 12.

By housing a coiled spring within the center piece of a hinge constructed according to my invention I have provided a construction 20 which may be readily and quickly secured in place in a last without any cutting or fitting except that required to form the sockets which receive the butt-pieces of the hinge—that is to say, when a last constructed according to my invention is provided with a 25 spring coiled inside of the center piece of the hinge the spring and the three pieces constituting the hinge may be first assembled and fitted together and a proper tension imparted 30 to the spring before securing the same in position in a last at all—whereas in all previous forms of hinged lasts with which I am familiar in order to apply a spring thereto the last-sections themselves have to be cut or variously fitted to receive the spring, and the 35 tension of the spring itself in such constructions can only be tested after the complete last is assembled.

I am aware that many changes may be made 40 in practicing my invention by those who are skilled in the art without departing from the scope thereof as expressed in the claims. I do not wish, therefore, to be limited to the construction I have herein shown and described; but

What I do claim, and desire to secure by Letters Patent of the United States, is—

1. In a last, the combination of the fore part, the heel part, a hinge for connecting 50 said parts, comprising a sheet-metal butt-piece fitting into a vertical socket in the fore part, a sheet-metal butt-piece fitting into a vertical socket in the heel part, so that said butts will extend at right angles to the axis 55 of the hinge, each of said butt-pieces having a single ring or eye, and a center piece of sub-

stantially twice the thickness of said eyes forming the pintle about which said butt-pieces may turn, said parts being arranged so that the center piece will extend both into 60 the fore part and heel part of the last.

2. In a hinged last, the combination of the forepart, the heel part, and a three-piece hinge comprising a flat metal butt-piece fitting into a vertical socket in the heel part of the last 65 at right angles to the axis of the hinge, a flat metal butt-piece fitting into a vertical socket in the fore part of the last at right angles to the axis of the hinge, transverse pins extending parallel with the axis of the hinge for securing the butt-pieces in the fore part and heel part of the last respectively, and a hinge center piece or disk forming the pivot of the hinge, which center piece is held from lateral displacement with respect to the butt-pieces 75 by fitting into the vertical sockets of both the fore part and the heel part of the last.

3. In a hinged last, the combination of the fore part, the heel part, a three-piece hinge comprising a flat metal butt-piece fitting into 80 the heel part of the last, a flat metal butt-piece fitting into the fore part of the last, a hinge center piece, and a spiral spring mounted in the hinge center piece for normally holding the parts of the last in line with each 85 other, said parts being arranged so that the flat metal butt-pieces are located in planes at right angles to the axis of the hinge.

4. In a hinged last, the combination of the fore part, the heel part, a flat metal butt-piece fitting into the fore part of the last, and secured in position by transverse pins which are parallel with the axis of the hinge, a flat metal butt-piece fitting into a socket in the heel part of the last, and also secured in place 95 by transverse pins parallel with the axis of the hinge, a tubular hinge center piece held in place from lateral displacement with respect to the butt-pieces by fitting into the sockets of the fore and heel parts of the last 100 respectively, and a spring coiled in the form of a spiral within the tubular hinge center piece, and connected to normally hold the fore and heel parts of the last in line with each other. 105

In testimony whereof I have hereunto set my hand in the presence of two subscribing witnesses.

MICHAEL F. GLEESON.
